UNITED STATES PATENT OFFICE

PAUL SCHÖNFIELD, OF CHEMNITZ, GERMANY

HOSIERY

Application filed September 17, 1930, Serial No. 482,559, and in Germany May 22, 1930.

The present invention relates to a method of producing hosiery of the type provided with tops.

Hosiery, especially of three-quarter length, having a single or double top with a jacquard or plaited pattern is known to the art in a variety of styles, but the manufacture of it is restricted in so far as fine-meshed hose cannot be provided with a top of coarser gauge or vice versa, at least not in a manner insuring perfect linking of both parts. This difficulty is due to the impossibility of transferring in a satisfactory manner a fabric to the needles of a machine having a finer or larger gauge than the fabric itself.

Attempts have been made already to transfer a fabric of a coarse gauge to the needles of a machine of finer gauge and to link on the hose in the usual manner. However, as the gauge and number of loops of the fabric did not correspond to the gauge of the machine, the fabric could be transferred only imperfectly and not within the course so that the transferred courses ravelled and the entire fabric or a part thereof dropped off from the needles. These drawbacks are eliminated by the invention.

According to the invention, a fine-meshed leg is linked on to a coarser-meshed top with a jacquard or plaited pattern or a coarse-meshed leg to a fine-meshed top by transferring the latter at a certain distance from its edge to the needles of a hosiery machine in the known manner and by turning back the portion in front of the needle points so that the top is transferred twice so to speak. In this way a small pad is formed at the transfer points and thus a completely closed edge. As this transferring manner prevents raveling, the top can be united with the leg in an absolutely perfect way.

The invention is illustrated in the accompanying drawings which disclose two forms of application of the method.

Figure 1 is a front view of a patterned fabric having the size of a regular top and ready to be turned at its edge to be transferred to the hose according to one modification of the invention; Fig. 2, a side view thereof; Figs. 3 and 4 indicate how the fabric with its turned

double edge, according to Figs. 1 and 2, is transferred to the needles of the machine linking on the leg; Fig. 5 is a view of a patterned fabric top; Figs. 6 to 8 show how the fabric is transferred to the needles of a hosiery machine in a modified way; and Fig. 9 is a view of a finished hose with partly opened double top.

Referring to the drawings, in Figs. 1, 2, 3 and 4 the fabric 1 provided with a plaited or similar pattern 2 and corresponding in size to a hose top has its upper edge turned back to produce the closed edge 5 (Figs. 1 and 2) which thus consists of two layers of fabric and is transferred to the needles 6 of a hosiery machine (Fig. 3) with the back, i. e., the small reversed portion 21, up, and the hose 7 (Fig. 4) is then worked on in the known manner. The transferring can take place on a transfer device, the top picked up being finally arranged on a transfer bar of known type by means of which it is transferred to the needles of a hosiery machine which need be stopped only while the transfer of the top is going on so that the loss in production is not greater than in tickling off a normal double top.

According to a modified method, the fabric 1 having the plaited or similar pattern 2 and the size of the regular top is transferred with its upper edge 3 behind the line 4 to the needles 6 of the hosiery machine (Fig. 6), whereupon the entire fabric 1 is pulled up so that the points 19 of the needles 6 engage the loops 20 of the portion 21 of the fabric lying in front of the needle points (Fig. 7). As shown in Fig. 8, the portion 21 is then turned back over the needle heads, to the closed edge of the hose. As shown in Figure 8 the portion 21 is then turned back over the needle heads and said portion is linked on in the usual manner to form a closed edge thus completing the hose.

The second method is inferior to the first one in so far as during the raising of the fabric and the turning back of the portion 21 the points 19 of the needles 6 can be easily broken or bent, and this manner of transferring can therefore, be carried out only by highly skilled operators. Moreover, during the

transferring process according to this modified method, which is quite a tedious affair, the entire hosiery machine must be stopped, which involves a considerable loss in production. To avoid this, the top might be transferred to a special device, which is quite a difficult task particularly when close goods are concerned. Besides, the transfer of the top to the needles of a hosiery machine is no easy work per se.

In both cases, however, a closed edge will be formed at the transfer points of the top, owing to the turning back of the portion 21, so that an absolutely satisfactory union of top and hose is insured.

If the top portion 1 is to be made into a double top 10, according to Fig. 9, the open portion 1 must be closed by connecting the upper edge 11 with the edge of the portion 21 by means of the seam 12, a solid rubber band 15 having previously been sewn to the back of the inner top portion.

If hosiery is made according to the invention, the advantages obtained are, firstly, that a fine-meshed hose 16 can be united with a coarse-meshed top having a jacquard pattern, or vice versa, and, secondly, that the patterned tops can be manufactured in one continuous band so that the pattern machine can be utilized fully and production becomes highly economical.

The top may consist of patterned, single-sided, ribbed or warp goods, the latter being particularly suitable on account of their great variety of patterns.

Furthermore, instead of linking the hose to the top transferred according to the invention, the process might be reversed and fancy legs transferred in the manner shown, whereupon a unicolored top could be worked on.

The goods 1 are folded over, and then pulled slightly upwards so that the needles on uniting the new portion to the other strike below the folded-over part, to form a joint or connection that will not ravel.

I claim:—

1. Method of producing hosiery with tops, according to which a piece of fabric having the size of a top is transferred at a distance from its edge to the needles of a hosiery machine and the portion of the fabric lying in front of the needle points turned back so that the top fabric being penetrated twice by the needles of the hosiery machine produces a closed edge on the transfer line.

2. A method as claimed in claim 1, according to which the fabric forming the top is doubled at the edge to be transferred, transferred near the edge thus closed to the needles of a hosiery machine, and provided with the leg and foot.

3. A method as claimed in claim 1, according to which the fabric forming the top is transferred at a distance from its edge to

the needles of a hosiery machine, pulled up to the points of the needles which penetrate it in front of the transfer line, and turned back over the needle heads with the portion lying in front of the points, the leg and foot being worked on to the edge thus doubly transferred.

4. A method as claimed in claim 1, according to which the leg of a hose is transferred to the needles of a knitting machine and the top linked on to it.

In testimony whereof I hereunto affix my signature.

PAUL SCHÖNFIELD.
